UNITED STATES PATENT OFFICE.

CHARLES A. CRIQUI, OF BUFFALO, NEW YORK.

POWER BOAT.

1,401,963.

Specification of Letters Patent. Patented Jan. 3, 1922.

Application filed November 7, 1918. Serial No. 261,534.

To all whom it may concern:

Be it known that I, CHARLES A. CRIQUI, a citizen of the United States, residing at Buffalo, in the county of Erie and State of New York, have invented new and useful Improvements in Power Boats, of which the following is a specification.

This invention relates to motor-driven boats of the type having a tunnel in which the propeller is arranged.

A boat of this character is shown and described in Letters Patent of the United States No. 1,108,840, granted to me August 25, 1914.

15 In order to obtain the highest efficiency of the propeller, the tunnel must at all times be filled with water, and this necessitates the removal of the air from the upper portion of the tunnel.

20 The object of my invention is the provision of a simple, efficient and inexpensive device for this purpose which dispenses with a pump or other power actuated means.

In the accompanying drawings:

25 Figure 1 is a sectional elevation of a flat-bottomed boat embodying the improvement. Fig. 2 is a sectional rear view thereof. Fig. 3 is a fragmentary longitudinal section of the tunnel, on an enlarged scale, showing a modified form of the ejector-tube.

Similar characters of reference indicate corresponding parts in the several views.

30 1 indicates the hull of the boat, 2 the propeller mounted on the shaft 3, and 4 a suitable motor, such as a gas engine, for driving the propeller-shaft, in the usual manner.

Secured within an opening in the bottom of the boat is a tunnel 5 which may be of any suitable construction, but which is preferably made of sheet metal separate from the hull and portable, like that shown in the Letters Patent hereinbefore referred to. This tunnel is open at its bottom and its rear end as usual.

45 Above the propeller the tunnel has the usual hand or manhole through which access is had to the propeller and its shaft for clearing the same of weeds, or for other purposes. This hole is closed by a cover 6 clamped in place by a screw 7. The latter

50 engages a yoke 8 removably interlocked with a fixed ring 9 by any suitable means. The customary watertight hood or well 10 encloses this ring. It is of sufficient height 55 to extend above the water level when the

boat is loaded, in order that access may be had to the submerged propeller after removing the cover 6, without flooding the boat.

Communicating with the upper portion of the tunnel is an air-ejector of any appropriate construction which is operated by the rearward current of the water created by the propeller. The preferred ejecting device shown in the drawings comprises an open-ended tube or pipe 11 arranged lengthwise in the upper part of the tunnel and extending from the highest point thereof to its rear end. The tube is carried by hangers 12 and its rear portion is preferably bent 70 or curved downwardly, as shown at 13. Surrounding or enclosing the rear portion of the tube is a U-shaped hood or funnel 14 secured to the deck of the tunnel and separated from the tube by an intervening space 75 or passage 15 through which a portion of the rearwardly-flowing water passes, thereby creating a partial vacuum at the adjacent end of the tube and exhausting the air from the tunnel. In order to obtain the best results, this ejector-hood is tapered from its front toward its rear end, as shown. The air being thus displaced, the tunnel space above the normal water-line will be filled 80 with water, avoiding cavitation at the propeller and obtaining its maximum efficiency.

85 In cases where the manhole cover 6 is located higher than the top of the tunnel 5, as illustrated in Figs. 1 and 2, the front end of the ejector-tube 11 may be curved and extended upwardly into the well 10, as shown at 11^a; while when the cover is located at the top of the tunnel, as illustrated in Fig. 3, the front end of the tube may be straight or horizontal, as shown at 11^b.

90 By utilizing the current produced by the propeller as the operating means of the air-ejector, no separate power-actuated device, such as a pump, is required for this purpose, providing an exceedingly simple and inexpensive contrivance. At the same time its construction and location are such that it does not interfere with the speed of the boat.

95 I claim as my invention:

1. The combination of a boat having a propeller-tunnel, and air-ejecting means connected with said tunnel and operated by the water-current through the same.

2. The combination of a boat having a propeller-tunnel, and an air-ejector, includ-

ing an exhaust conduit extending from the upper portion of the tunnel toward its open rear end.

3. The combination of a boat having a propeller-tunnel, an exhaust-tube extending from the upper portion of the tunnel to its open rear end, and an ejector-hood arranged within the tunnel and enclosing the rear end of said exhaust-tube.

10 4. The combination of a boat having a propeller-tunnel, a well extending upwardly from the tunnel, a manhole cover in said

well, and an air-ejector arranged in the tunnel and including an open-ended exhaust-tube terminating near the rear end of the 15 tunnel and extending upwardly into said well.

5. A boat-tunnel carrying air-ejecting means, comprising an exhaust-tube extending from the upper portion of the tunnel to 20 its rear end and an ejector-hood enclosing the discharge end of said tube.

CHARLES A. CRIQUI.
